DESIGN FOR A BALL COCK BODY

Herbert D. Clemons, Sturgis, Mich., assignor
to Scovill Manufacturing Company, Sturgis,
Mich.

Application July 6, 1936, Serial No. 63,655

Term of patent 14 years

To all whom it may concern:

Be it known that I, Herbert D. Clemons, a citizen of the United States, residing at Sturgis, in the county of St. Joseph and State of Michigan, have invented a new, original, and ornamental Design for a Ball Cock Body, of which the following is a specification, reference being had to the accompanying drawing forming part thereof, in which:

Fig. 1 is a top plan view,

Fig. 2 is an elevation looking from the left of Fig. 3,

Fig. 3 is an elevation looking from the right of Fig. 2, and

Fig. 4 is a vertical central section of a ball cock body, showing my new design.

I claim:

The ornamental design for a ball cock body, as shown.

HERBERT D. CLEMONS.
